UNITED STATES PATENT OFFICE

128,400

DESIGN FOR A CABLE CONNECTOR

James B. Miller, Webster Groves, Mo.

Application March 23, 1940, Serial No. 91,198

Term of patent 14 years

To all whom it may concern:

Be it known that I, James B. Miller, a citizen of the United States and a resident of the city of Webster Groves, county of St. Louis, State of Missouri, have invented a new, original, and ornamental Design for a Cable Connector, of which the following is a specification, reference being had to the accompanying drawing, forming part thereof and in which—

Figure 1 is a plan view of a cable connector embodying my new design; and

Figure 2 is a perspective view taken from the left end of Figure 1.

The opposite side of the device is substantially similar to that shown.

The essential features of the design are shown in full lines.

I claim:

The ornamental design for a cable connector, substantially as shown and described.

JAMES B. MILLER.
